UNITED STATES PATENT OFFICE.

AXEL FERDINAND OLSSON WILCK, OF STOCKHOLM, SWEDEN.

PUSH-BUTTON.

1,306,092.

Specification of Letters Patent. Patented June 10, 1919.

Application filed February 6, 1919. Serial No. 275,367.

To all whom it may concern:

Be it known that AXEL FERDINAND OLSSON WILCK, subject of the King of Sweden, residing at Surbrunnsgatan 51, Stockholm, in 5 the Kingdom of Sweden, has invented certain new and useful Improvements in Push-Buttons, of which the following is a specification.

My present invention has for its object an 10 improved push button adapted to be used on shoes, gloves and similar articles. The push button consists as usually of two parts, viz., an upper part adapted to be fastened to one of the leather members and containing a 15 spring, and a lower part adapted to be fastened to the other leather member and containing a hook or similar locking device which, when the parts are in locking position catches a locking member on the other 20 part and is held forced against the same by the spring.

The characteristic feature of my invention now consists in this that the spring 25 comprises a circular portion being fastened on the upper button part and that at one place the said spring is formed to a tongue extending obliquely upward from the same in such a manner that, when the hook or other locking device is inserted through a 30 hole in the bottom of the upper button part, said tongue exerts a pressure on the hook both laterally and downward. By this arrangement the advantages are gained that the spring as well as the fastening of the 35 same will be very strong and durable, and, moreover, that the opening of the button can be effected by merely displacing the upper button part to the side against the action of the spring a sufficient distance after which 40 the tongue of the spring presses the locking member downward through the hole so that the parts are automatically separated without having the necessity of pulling the parts from one another as is the case with the but- 45 tons now in use.

The invention is illustrated on the accompanying drawing where Figure 1 shows a sectional view of a push button. Fig. 2 is a plan view of the same and Fig. 3 shows a 50 modified form.

1 and 2 are the ends of the material, for

instance leather, in which the button parts 3 and 4 are fastened. The part 4 is provided with a hook or locking member 5 adapted to be inserted through an opening 6 provided 55 in the bottom of the upper part. In this position the spring tongue 10 presses the hook 5 against the edge of the opening 6 and the hook is locked in this position by a groove 8 surrounding the same. 60

The spring consists of a circular part 7 over which the sleeve shaped portion 9 of the upper button part is bent down so that the spring is rigidly held fast between the bottom and the bent down portion of the 65 sleeve. The spring is curved in the manner shown in Fig. 2 so that a tongue 10 is formed on the same, said tongue extending from the circular portion 7 in an oblique direction upward. By this means the spring will exert a pressure on the hook not only to the side but also downward. When opening the 70 button it is only necessary to displace the upper part laterally (to the left in Fig. 1) against the action of the spring a distance 75 sufficient for releasing the hook from the edge of the opening 6. Then the hook is forced down through the opening by the pressure of the spring and the parts of the button are automatically separated from one 80 another.

The sleeve shaped part 9 is forced into a hollow head 13 indicated with dotted lines in Fig. 1. A similar head 12 of sheet metal is forced over the sleeve shaped portion 11 of 85 the lower button part 4. When pressed together the edges of the sleeve are folded down as indicated by dotted lines, whereby the button 12 becomes flat.

The form of embodiment according to 90 Fig. 3 differs from that one shown in Fig. 1 only in this that the sleeve shaped portion is omitted and that the button parts are attached to the leather by sewing.

Having now described my invention, what 95 I claim as new and desire to secure by Letters Patent is:

In push buttons the combination of two 100 separate button parts, an opening in the bottom of the one part, a circular spring portion fastened in the same, a spring tongue extending obliquely from said circular

spring portion, a hook member in the other button part adapted to be introduced through said opening, the spring tongue being located in such a manner that it exerts a pressure on the hook both to the side, so as to press it against the edge of the opening, and downward so that the button parts are automatically separated by displacing one

button part to the side against the action of the spring.

In testimony whereof I have affixed my signature in presence of two witnesses.

AXEL FERDINAND OLSSON WILCK,
Witnesses:

AXEL EHRNER,
I. A. W. O. BAGGS.
